UNITED STATES PATENT OFFICE.

RICHARD L. LLOYD, OF NEW YORK, N. Y., ASSIGNOR TO DWIGHT & LLOYD SINTERING COMPANY, OF NEW YORK, N. Y., A CORPORATION OF DELAWARE.

SINTERING MACHINE.

Application filed October 13, 1919, Serial No. 330,482. Renewed June 19, 1923.

To all whom it may concern:

Be it known that I, RICHARD L. LLOYD, citizen of the United States, residing at New York, in the county of New York and State of New York, have invented certain new and useful Improvements in Sintering Machines, of which the following is a specification, reference being had therein to the accompanying drawing.

10 This invention relates to improvements in apparatus for igniting the ore in sintering devices. Heretofore this igniting has been effected by flames of gas or vapor or liquid fuel applied to the surface of the ore. But 15 these methods are often very expensive because the gas or liquid fuel must be transported great distances and often for this purpose only. Coal, however, is required at nearly all places to furnish power at the 20 mines for the mining and the handling of the ores, and at such places the greater amount of the sintering is performed.

And, again, many sinterable ores refuse to ignite quickly at their surfaces, and if 25 flames of gas or vapor are utilized for ignition it is necessary to spread them out over a large area of the ore while it is moving along under the igniter in order to have the top ore particles subjected for a long period 30 of time to the gas flames. This necessitates the use of a large amount of the expensive igniting fuel.

The purpose of the present invention is to provide an igniter, for use with a sintering apparatus, which will utilize a small amount of solid coal in reduced condition, as the igniting fuel, and have this solid coal so regulated, as to the size of its particles, and as to its proportion to the air volume, that 40 its particles can be utilized as igniters for a long period at points adjacent the top particles of the ore.

My device is well adapted for use with sintering machines of that class in which each 45 includes a series of small ore carrying cars or pallets, which in turn, successively, (a) receive charges of ore, (b) pass under an igniting device which sets up combustion in the top strata of the ore charge; (c) pass 50 over an air suction chamber or under an air blast chamber which causes the combustion to pass downward thru the mass of material in the car, (d) then discharge the ore after the sintering process has been completed, 55 and (e) then return for new charges of ore.

It will be found adapted also for use with sintering and roasting mechanisms of other kinds without departing from the spirit of the invention, provided proper modifications are made.

For clearness I have omitted from the drawings many of the details of construction of the sintering apparatus, as an entirety, showing only those which relate more particularly to the matter of ignition. A 60 complete description of the construction and operation of such a sintering apparatus as is indicated herein, is given in Letters Patent No. 1,027,084, issued to Henry J. Stehli, May 21, 1912, to which reference can be 65 made.

Fig. 1 is a view, largely diagrammatic, showing some of the parts of a sintering apparatus in section, on the central vertical transverse plane of the igniting apparatus, 75 and showing the fuel supplying devices in elevation.

Fig. 2 is a sectional view of the mechanism for forming, and supplying to the ore igniter powdered fuel.

Fig. 3 is an elevation of the rotary part of the grinding mechanism, and showing the casing in section.

Fig. 4 shows in section the nozzle for supplying fuel to the igniter.

In the drawings the usual main framework is indicated, it having uprights 1, 1, bottom cross bars 2, upper cross bars 3, and suitable brace bars of the required number and dimensions, all bolted securely together 90 in the usual way to form a rigid support for the various parts of the sintering apparatus. 4, 4 and 5, 5 indicate the usual track rails supported on the said framework. On these rails are fitted the wheels 6, 6 of the ore cars 95 or pallets 7, 7. In its upper position in Fig. 1, the pallet 7 is traveling away from the observer and away from the feeding hopper 54; and in the lower position, it having discharged its contents, is returning toward 100 the observer. These pallets, 7, 7, comprise the retaining side walls 9, 9, and the bottom parts 8, which are grate-like in construction, retaining the ore material in the car, but permitting the passage of air currents. 10 105 is the air chamber over which the pallets, containing the ignited ore, pass; and 11 is a duct leading from this chamber 10 to a suitable fan or suction device which causes currents of air to flow down through the ore in 110

the cars, into the chamber 10, and then through the pipe 11 to the suction mechanism. This draft causes the combustion to travel downward thru the strata of the ore 8 while the pallets are passing over said chamber 10, 12, 12 are channel irons secured to the cross bars 3, to support the air chamber walls 10, which are provided with outwardly flaring edge parts, 13, 13, and the wearing 10 bars 14, 14, secured to the shoulders 15, 15, of the edge parts 13, 13. The wearing bars 14, 14, insure a tight connection between the bottom edges of the sides of the ore carrying pallets 7 and the upper edge parts 13, 13, of 15 the chamber 10, a requisite feature for efficient operation of the air suction devices. 16 is a door to permit access to the interior of the air chamber 10, for the removal of accumulations of ore particles which might be 20 drawn thru the grate bottoms of the pallets by the force of the air draft.

18 designates, as an entirety, the igniting device, it being shown as a box suspended over the pallet path by the hangers 19, 19, 25 which are secured to a part of the framework not shown, in any suitable manner. This ignition chamber comprises the roof 20, the front wall, 21, and a rear wall similar thereto, the solid side wall 22 and the 30 opposite side wall 23, having an aperture 24. The width of the box 21 is made somewhat greater than the width of a pallet, for a purpose hereinafter described. The lip 25 decreases the width of the open area at 35 the bottom to equal the distance between the pallet walls 9, 9. 26 is a pipe leading from the blower or air pump 27 and having the horizontal section 28, the latter terminating in the nozzle 29 which is positioned 40 in the aperture 24. 30 is a pipe leading to the blower 27, it having a horizontal section 31 which at 32 bends downward and enters an enlarged chamber 33. The lower part 45 of this chamber 33 tapers down to a throat, part 34, which is fitted tightly to a large hopper 35. The blower fan 27 is mounted on a shaft 36, carried in bearings 37, 37, on a pedestal 38, 39 is a grinder or crusher mounted on the pedestal 38. It consists of 50 the stationary disc 40, and the rotating disc 41, the latter secured to one end of the shaft 36. 42 is an inclined feed duct leading from the bottom of the hopper 35 thru the casing of the grinder 39, and thru the stationary disc 30 under control at 51 of gate 55. The end of this feed duct is concentric with the rotary grinding disc 41 and discharges material from the hopper 35 at points between the inner grinding surfaces 60 of the disc 40 and 41. 43 is a rectangular opening in the front wall of the grinder casing and 44 is a pipe leading from a similar opening in the rear wall of the casing to a point intermediate of the top and bottom 65 of the chamber 33, into which it leads.

Power is applied to the shaft 36, for rotating the air pump 27 and grinder 39, by a belt on the pulley 45, which latter is keyed to the shaft 36. 46 is a removable air tight door for the hopper 35 thru which the coal 70 or its equivalent may be supplied thereto.

The method of operation of my improved device will be readily understood. After the hopper 35 has been charged with coal or its equivalent, and the door 46 tightly 75 closed, power is applied to the shaft 36, and the blower 27 and the grinder 39 are put in operation. Coal passes by gravity from the hopper 35 thru the pipe 42 to the grinder 80 39 where it is pulverized between the discs 40 and 41, and then carried, again by gravity, to the bottom of the grinder casing. In the meantime a current of air controlled by suitable valves as at 53, has been set up by the pump 27 which is drawing the air in 85 at the orifice 43 and creating a suction in the duct system consisting of the pipe 44, the chamber 33 and the pipe 30, 31. The pulverized material is drawn from the grinder 39, up thru the pipe 44 and into the 90 chamber 33. At this point, because of the enlarged diameter of the chamber, compared with the pipe 44, and the consequent reduction in carrying power of the air blast, the relatively large particles of the coal dust 95 fall back into the hopper, and the relatively smaller particles are carried up into the pipe 31 and down thru the pipe 30 to the blower 27. From this point they are forced by air pressure up thru the pipe 26, 28 under 100 control of suitable valves, as at 52, and out thru the nozzle 29 and into the ore firing box, where they can be easily ignited, initially by an external flame and thereafter by internal combustion.

The ignition box 18, acting as a holder, will direct the hot particles downward to the surface of the ore, but this deflection does not commence until the fuel reaches vertical lines some distance in from the nozzle 29. 110 If the nozzle were placed directly over one side wall 9 of the pallet, the ore adjacent that wall would not be impinged on by the burning particles from the nozzle. Hence the box 18 is made wider than the pallets, as described above, so that the nozzle can be set back from the vertical line of the edge of the pallet to insure an even distribution of the hot particles over the entire top strata of the ore.

115 Admission of a sufficient amount of air to secure ignition of the coal particles in the chamber 18 is assured by the large orifice 24 which has a greater diameter than that of the nozzle 29 and affords easy entrance of air which is drawn in by the suction created by the discharge at the mouth of the nozzle. The air so entering can be regulated by dampers, or the like, at 47, to correspond with the quantity of air in the 120 125

fuel mixture that is delivered from the nozzle, under control of suitable valves as at 48, 49.

The devices which grind or comminute 5 the carbon are arranged so as to be adjustable in any of the well known ways to effect a coarser or a finer reduction at discretion; and, similarly, the ducts are provided with 10 adjustable valves, or equivalents, for regulating the volume and the force of the currents of air which move upward with the coal particles.

The flames delivered to the surface of 15 the ore which are obtained by the burning of gases, such as illuminating gas, or those obtained from the burning of oil have only a brief action upon the ore as it is moving along, and many ores, when being sintered, refuse to quickly light at all points over the 20 surfaces, and an imperfect ignition is secured. But I have succeeded in providing an igniting agency, the particles of which will maintain a more prolonged period of burning, as the carbon can be delivered in 25 such relatively large proportion that the particles after becoming heated will fall upon the ore surface and remain there in a hot condition while completing their burning and will transmit heat to the ore surface 30 for a longer time than will the flames obtained from gas or vapor.

What I claim is:

1. In an ore sintering apparatus, the combination of means for forcing air thru a 35 predetermined area of an ore stratum, means

for supporting a stratum of sinterable ore and for advancing it past and in operative relation with the said air forcing means, means for supplying ore to the supporting means and for forming a uniform stratum 40 thereon while the supporting means are moving toward the air forcing means, means for supplying, in a stream, a combustible mixture of air and powdered solid carbon, and a holder adjacent the ore and arranged 45 to receive said stream and direct the flames of combustion of the powdered solid carbon to the surface of the ore while it is moving from the ore supplying means to the air forcing means. 50

2. In an ore sintering apparatus the combination of means for forcing air through a predetermined area of an ore stratum, means for supporting a stratum of sinterable ore in operative relation with said air 55 forcing means, means for supplying ore to the supporting means, means for supplying in a stream a combustible mixture of air and pulverized solid fuel, and a receptacle adjacent the surface of the ore and arranged 60 to receive said stream of pulverized fuel and direct the flames of combustion to the surface of the ore, the receptacle and the ore support being related substantially as described to cause particles of incompletely 65 burned ore to be deposited on the ore.

In testimony whereof, I affix my signature.

RICHARD L. LLOYD.
